UNITED STATES PATENT OFFICE.

SAMUEL R. FRAIM, OF LANCASTER, PENNSYLVANIA.

PADLOCK.

Application filed October 27, 1926. Serial No. 144,543.

This invention relates in general to improvements in padlocks and more particularly in the type generally employed for the purpose of locking spare wheels on tires to automotive vehicles.

The object of this invention is the provision of a shackle of novel form to engage the lugs, used to secure a tire on the spare wheel rim, in such a manner as to conform with the lugs and prevent movement of the removable member or the unauthorized insertion of a tool for separating the shackle from the casing without unlocking the padlock.

Another object is the provision of a cushioning member in the upper edge of the padlock casing adapted to coact with the improved shackle for the purpose of further eliminating relative movement of the locking assembly and the consequent rattling.

A further object is the provision of a novel locking bolt to engage the closely spaced notches of the improved shackle, whereby a finer adjustment will be possible in order to force the locking bracket against the shackle and cushioning member as a rattling preventative.

With the foregoing and other objects in view the invention consists in the combination of parts and in the details of construction hereinafter set forth, certain embodiments being illustrated in the accompanying drawings, in which—

Figure 1 is a view in front elevation of the padlock casing and shackle in assembled position;

Figure 2 is a vertical section through the casing showing the manner of attachment of the cushioning device to the casing;

Figure 3 is a vertical section through a portion of the spare tire rack and securing brackets, showing the padlock attached thereto.

Figure 4 is a view in front elevation partly in section, of the padlock with part of one face of the casing removed.

Figure 5 is a detail perspective of one of the locking bolts of the padlock.

Referring more particularly to the drawings, the shackle has two legs 2 and 3 both of which pass through the casing 1. The leg 2 is straight while the leg 3 is bent outwardly at 3^a at its upper extremity from parallelism at an obtuse angle. The leg 3 is bent back into parallelism with the leg 2 at a point 3^b.

As shown in Figure 2 a cushioning member 4 of suitable flexible material, such as rubber, is fitted in the upper edge of the padlock casing. The member 4 consists of a reduced portion 4^a and an enlarged flanged portion 4^b to retain it in the casing. This cushioning member is so fitted that it may be replaced by merely separating the two halves of the ordinary casing and slipping the reduced portion 4^a in the aperture of the casing.

As shown in Figure 4 the locking mechanism comprises a pair of opposed locking bolts 11, with enlarged end portions 11' having a plurality of teeth 12 adapted to engage the closed spaced notches 2' and 3' of the shackle legs 2 and 3. The bolts 11 have apertures 13 which are engaged by a key to slide the bolts one upon the other against the actions of the springs 14 into an unlocked position. Upon removal of the key the springs 14 force the bolts into a position where they are adapted to engage the shackle in locked engagement. The main feature in this connection as applied to the present invention is the provision of the closely spaced notches on the shackle legs, and the plurality of meshing teeth on the sliding locking bolts. This allows the casing and the shackle to be more precisely adjusted, in relation to the member to be locked, in such a manner that the cushioning member 4 is forced against the locked member, and inasmuch as the bent shackle conforms with the locked member 90 on its other side, the possibility of rattling is effectively eliminated.

In Figure 3 is shown a particular adaptation of the improved padlock assembly. The spare tire securing means shown consists of a skeleton rim or plate 9 and a demountable rim 10 within which a pneumatic tire or spare casing is mounted. The rim 10 is loosely fitted over the plate 9 and an angle iron lug or bracket 5, bolted at 11 to the plate 9, is provided with an orifice near the upper extremity of its upright portion and an opposing removable lug 6, having at its lower end a wedge-like portion 6', is normally held with the portion 6' lying between the plate 9 and the rim 10, tending to spread them apart, and secured to the tire rack in the usual manner by a fastening bolt 7 with its corresponding nut 8.

The brackets 5 and 6 are provided with aligned apertures through which the straight leg 2 of the shackle is passed. The two

2
brackets 5 and 6 are also provided with open-ended slots at their upper extremities to receive the bent leg 3 of the shackle which rests in snug engagement. Obviously to lock the bracket assembly the casing 1 is placed on the two protruding shackle legs.

Figure 3 shows the snug engagement of the particular type of offset shackle described, together with the cushioning member 4 pressed against the bracket 6. The bend in the shackle, while producing in this particular use, does not involve any great amount of expense or precision, which is due to the simplicity of its nature. This feature combined with the inexpensive and simple

replaceable cushioning device, constitutes an excellent anti-rattling locking device which makes for efficiency as well as economy.

I claim—

In a padlock, a casing, a substantially U-shaped shackle the legs of which pass through said casing, said casing having a cushioning member mounted in the upper edge thereof between the joined legs of said shackle, said cushioning device consisting solely in a solid member of flexible material reduced at its mid-portion and removably fitted in said casing.

In testimony whereof I affix my signature.

SAMUEL R. FRAIM.
